UNITED STATES PATENT OFFICE.

WICTOR WISNIEWSKI, OF NEW YORK, N. Y., ASSIGNOR TO POLISH FALCONS ALLIANCE OF AMERICA, OF PITTSBURGH, PENNSYLVANIA, A CORPORATION OF ILLINOIS.

DESIGN FOR A BADGE, PIN, BUTTON, EMBLEM, INSIGNIA, OR SIMILAR ARTICLE.

44,949.

Specification for Design.

Patented Nov. 25, 1913.

Application filed October 16, 1913. Serial No. 795,574. Term of patent 14 years.

To all whom it may concern:

Be it known that I, WICTOR WISNIEWSKI, a subject of the Czar of Russia, residing at New York, in the county of New York and State of New York, have invented a new, original, and ornamental Design for a Badge, Pin, Button, Emblem, Insignia, or Similar Article, of which the following is a specification, reference being had to the accompanying drawing, forming part thereof.

The figure is a face view of a badge, pin, button, emblem, insignia, or similar article showing my new design.

I claim:

The ornamental design for a badge, pin, button, emblem, insignia, or similar article as shown.

WICTOR WISNIEWSKI.

Witnesses:

STEFAN STAMIROUSKI,
KAROL LICHOCKI.
